UNITED STATES PATENT OFFICE.

WALTER W. ROBINSON, OF CHICAGO, ILLINOIS.

ROTARY PUMP.

SPECIFICATION forming part of Letters Patent No. 767,442, dated August 16, 1904.

Application filed August 29, 1903. Serial No. 171,193. (No model.)

To all whom it may concern:

Be it known that I, WALTER W. ROBINSON, a citizen of the United States of America, residing at Chicago, in the county of Cook and State of Illinois, have invented certain new and useful Improvements in Rotary Pumps, of which the following is a specification.

My invention relates to certain new and useful improvements in rotary pumps; and its object is to produce a device of this class which shall be simple and cheap in construction and highly effective in operation.

To this end my invention consists in certain novel features of construction, which are clearly illustrated in the accompanying drawings and described in this specification.

In the aforesaid drawings, Figure 1 is an elevation of my improved pump, one of the side plates being removed to show the interior construction. Fig. 2 is a vertical longitudinal section through the same. Fig. 3 is a section in the line 3 3 of Fig. 2 looking in the direction of the arrow. Fig. 4 is a perspective view of the gate; and Fig. 5 is a view similar to Fig. 1, but showing the circular piston and gate in different positions.

Referring to the drawings, A is a chamber made in the form of a flat cylinder and having pipes B C extending from it. One of these pipes is an inlet-pipe and the other an outlet-pipe; but as this pump, like most rotary pumps, can be run in either direction either pipe may serve either of these purposes. In the center of the chamber A is a shaft D, upon which is eccentrically mounted a circular piston E, keyed against rotation by a key e. The piston is of such size that the point farthest removed from the shaft is in close contact with the wall of the cylinder A, and the thickness of the piston is the same as that of the cylinder, so that as the shaft D is rotated and the piston E moves around the chamber any fluid therein contained will be forced to move with it.

A hollow tube F is provided, extending radially from the chamber A, and in this tube is a gate G. A cap F' closes the top of the tube F, and a spring G' holds the gate G, which is made with a hollow center, in con-

tact with the piston E. A small perforation 50 g is provided at the lower end of the gate G, through which a lubricating substance can pass. The gate is in practice filled with some thick lubricating material. The peculiar feature of this gate is that it is circular in cross-section and that it is beveled at its point, as shown in the drawings. In building a pump it is much easier to use a circular gate than a gate of any other form, for the reason that the socket in which it reciprocates can be bored 55 out without any great difficulty, while a hole of any other shape is much more expensive to make. The difficulty, however, with a cylindrical gate squared at the bottom is that as the piston rotates the line of contact of the 60 gate therewith swings to one side from the other of the diameter, and a by-pass is provided through which the fluid in the pump can pass from one side of the gate to the other, and so not be forced out of the outlet-pipe. 65 Some means must therefore be provided for keeping the gate in contact with the piston upon a line diametrical of the gate, and this is accomplished by beveling the end thereof. To be theoretically perfect, the gate should 70 be beveled with two faces meeting in a mathematical line, the angle of the bevel being at least enough to make the faces tangent when the periphery of the piston presents the smallest angle to a line running longitudinal of the 75 gate. In practice, however, a gate beveled to a mathematical line would wear out too rapidly, and consequently the point is slightly rounded, but is of such shape as to keep the line of contact of the piston upon the periphery substantially at the diameter of the gate. When the gate is constructed in this manner 80 with a beveled end, it is not necessary to provide means for preventing the gate from rotating in the socket provided for it, for the 85 reason that the pressure of the spring G', which forces the gate into contact with the piston, makes it very difficult for it to occupy any other position than that shown in the drawings while the piston is in rotation. In 90 fact, with the piston rotated ninety degrees from the position shown in Fig. 1 a considerable amount of extra compression of the 95

spring must be effected before the gate can be rotated. The beveling of the point of the gate therefore has two very desirable features. First, it keeps the line of contact practically diametrical and prevents leakage past the gate, and, second, it prevents rotation of the gate.

I realize that considerable variation is possible in the details of this construction without departing from the spirit of the invention, and I therefore do not intend to limit myself to the specific form herein shown and described.

I claim as new and desire to secure by Letters Patent—

1. In a device of the class described, the combination with a suitable chamber having inlet and exhaust ports, of a rotatable piston eccentrically mounted therein, and a cylindrical spring-pressed gate beveled at its lower end,

extending radially from the chamber and in contact with the piston.

2. In a device of the class described, the combination with a chamber and inlet and exhaust ports connected therewith, of a rotatable piston eccentrically journaled therein, a cylindrical gate extending radially from the chamber, means for holding the gate in contact with the piston, the gate being provided with a beveled lower end, and no means being provided other than the beveled surfaces for preventing the rotation of the gate.

In witness whereof I have signed the above application for Letters Patent, at Chicago, in the county of Cook and State of Illinois, this 24th day of August, A. D. 1903.

WALTER W. ROBINSON.
